CARTON CLOSING DEVICE

Bernard L. Maxwell, Reading, Mass., assignor to
Lever Brothers Company, a corporation of
Maine

Application February 2, 1935, Serial No. 4,597

8 Claims. (Cl. 93—6)

This invention relates to packaging apparatus and particularly to apparatus for closing and sealing cartons.

In merchandizing packages of bulky products, such as soap flakes or powders, it has been found that cartons often reach consumers with the level of the contents noticeably below the top, sometimes to the extent of a half inch or more, although the cartons were full before sealing at the factory. This is objectionable and disadvantageous from a sales viewpoint inasmuch as customers, on noting that the level of the contents is below the top edges of the carton, may come to the conclusion that they have been given short measure whereas the discrepancy between the capacity of the carton and the quantity of material therein is actually a result of the shrinkage in the volume of the contents due to natural settling thereof after packaging or because of considerable jarring of the cartons while in transit.

To correct this undesirable condition it has been proposed to place a greater quantity of material in the package by heaping it above the top and mechanically compressing the contents to the top edge of the carton by means of a plunger before closing and sealing the flaps. However, this procedure has not been entirely successful because the compression of such products as soap flakes by a mechanical plunger often results in breaking the flakes and removing the crinkle therefrom so that the product does not reach the consumer in its natural condition. Moreover, undesirable shrinkage in the volume of the contents, as mentioned above, is still found to take place due, in part, to the fact that when a plunger is used it enters about two thirds of the way into the carton, thereby compressing and breaking up the contents in the lower third of the carton. When the plunger is extracted it draws with it some of the product from the lower third of the carton into the upper two thirds thereof, thereby creating a condition in which the density of the product in the lower third of the carton differs materially from that in the upper two thirds. On subsequent handling of the carton before it reaches the consumer, the tendency of the lighter product in the upper two thirds of the carton is to settle in more compact form thus leaving an empty space at the top of the carton.

In a co-pending application Serial No. 757,633 filed December 15, 1934 there is disclosed carton closing and sealing apparatus for overcoming the above mentioned disadvantages by filling a car-

ton, with the end and side flaps extending vertically from the top edges thereof, to a level between the upstanding flaps and then closing the flaps to seal the carton, thus putting the material under pressure without diminishing its resiliency so that when the carton is opened its contents tend to expand again to above the top of carton. In addition to means for advancing the cartons through the machine and for closing and sealing the side flaps of a carton over its end flaps, the above mentioned application discloses apparatus for closing both end flaps simultaneously and for pressing the quantity of material located between the upstanding flaps into the body of the carton by means of the end flaps as the latter are folded inwardly to closed positions. In the illustrative embodiment of the invention disclosed in the prior application the end flap closing apparatus consists essentially of a pair of pivoted members, such as plates, operable in unison to close both end flaps simultaneously, one plate being pivotally mounted for engaging and closing one end flap of a carton at the closing station and the second plate being carried by the first plate and arranged for pivotal movement thereon, in a direction opposite to that of the latter, to engage and close the other end flap.

The apparatus of the present invention is, in its broader aspects, similar to that of the above mentioned application in that it also utilizes a pair of oppositely pivotable plates for closing the end flaps. However, as disclosed herein, the closing plates for the opposed end flaps of a carton are independently mounted and operated in unison by mechanism differing from that provided for operating the flap closing plates of the earlier application. In addition the platform on which a carton is supported at the end-flap closing station is arranged to operate in conjunction with the flap closing plates for pressing the material located between the upstanding flaps of a carton into the body thereof so that the packaged material is under pressure.

In the drawings:

Figure 1 is a plan view of carton closing apparatus embodying the present invention;

Figures 2 to 6 are perspective views showing a carton at various stages in the flap closing operation;

Figure 7 is a side elevation of a portion of the apparatus illustrated in Figure 1, and shows the end-flap closing apparatus;

Figure 8 is an enlarged view of the end-flap closing apparatus, some parts being omitted and

others shown in section to illustrate details of construction;

Figure 9 is a sectional view taken along the line 9—9 in Figure 8; and

5 Figure 10 is a view similar to Figure 8 but illustrating parts of the end-flap closing apparatus in another operating position.

Referring particularly to Figures 1 and 7, the 10 numeral 10 designates a continuously driven conveyor belt for carrying filled cartons away from a filling station (not shown) where they receive a measured quantity of soap flakes or similar bulky material. Each carton 11 reaches the filling station with the bottom sealed and the end 15 and side flaps 12, 13 and 14, 15, respectively, at the top thereof extending vertically upwardly from the sides so that the carton may receive a quantity of soap flakes filling it to a level between the upstanding flaps and above the score 20 lines 16 about which these flaps are turned inwardly and downwardly to close and seal the carton, as illustrated in Fig. 2.

Guide plates 17, spaced at a distance slightly 25 greater than the thickness of the cartons, extend along and above belt 10 to guide the cartons to a position in front of a reciprocatory offset-feed device. The offset-feed device removes the cartons in succession from belt 10 and delivers them to apparatus, designated as a whole 30 by the numeral 39, which is provided for closing the end flaps 12, 13 and which is disposed in offset relation to the conveyor belt, as shown in Fig. 1.

The forward movement of each carton 11 by 35 belt 10 is stopped by bars 18, 19 positioned to engage the forward end of each carton near the top and bottom thereof. Bars 18, 19 also serve to guide the cartons in their subsequent lateral movement by the offset-feed device which is disposed to reciprocate transversely of and above the conveyor belt. The offset-feed device comprises a member 20 fixed to a reciprocatory rod 21 and carrying a pusher plate 22 for moving a carton 11 off belt 10 onto a platform 23 located beneath the end flap closing apparatus 39 with the rear side face of the carton contacting vertically spaced back guides 24 and 24a. Plate 22 has an angular extension 25 for closing the exit at the forward end of guides 17 to temporarily stop the advance of the following cartons, belt 10 slipping beneath the cartons whose forward movement therewith is thus inhibited.

The reciprocation of rod 21 is effected and controlled by a cam 26 on a cam shaft 27 through 55 a lever system or other mechanism (not shown) adapted to convert the rotary movement of shaft 27 into a reciprocatory movement for rod 21 and the offset-feed plate 22 actuated thereby. The offset-feed cam 26 does not effect continuous 60 reciprocations of the offset-feed device but operates the latter only when the cam is tripped by a trigger 30. Trigger 30 extends adjacent bars 18, 19 and has one end positioned in the path of movement of a carton, as it is advanced from guides 17 by belt 10, so that when a carton becomes positioned in front of offset-feed plate 22, trigger 30 is actuated by the carton to cause tripping of cam 26 for effecting operation of the offset-feed device to transfer the carton to platform 23.

Cam 26 is formed with a cam slot or the like arranged to vary the rate of reciprocatory movement of pusher plate 22 by rod 21. In transferring a carton from belt 10 to platform 23

the plate 22 is initially moved at a sufficiently slow speed to obviate jarring of the carton in order to prevent spilling the soap flakes that fill the carton to a level near the top edges of the upstanding flaps. At the end of its inward stroke to transfer a carton, pusher-plate 22 remains in contact therewith for an interval while the end flaps 12, 13 are being closed and its angular extension 25 is positioned to prevent advance of other cartons by belt 10, Fig. 9. The return movement of pusher-plate 22 is at a more rapid rate to enable it to be positioned outwardly beyond guides 17 in sufficient time to transfer the following carton to platform 23 without undue delay as the plate 25, moving beyond the guides 15 17, permits belt 10 to position another carton in front of the pusher-plate 22 of the offset-feed device. Although a particular carton feeding device has been shown and described in detail, it should be understood that other types of feeding devices may be employed to position the cartons in succession beneath the device 39 for closing the end flaps.

The platform 23, to which the cartons are 20 transferred from belt 10 by offset-feeding device 20—22, is carried by an elevator foot 33 fixed to an elevating rod 34 reciprocable in guiding members 35, 36 on the machine frame. The member 35 is mounted on a bracket 42 supported above the platform 23 and also guides a second reciprocable rod 37. Rods 34 and 37 are operatively connected by means of a cross-head 38 secured to rod 34 and slidably mounted on rod 37. The end portion of cross-head 38 that 30 embraces the rod 37 is adapted to engage nuts 37a thereon for raising it in unison with rod 34 during part of the upward movement of the latter. A member 38a fixedly mounted at one end in cross-head 38 is bent adjacent its other end to extend over rod 37 in alignment therewith so that when the free end of the member 38a is brought into contact with the end of rod 37, as cross-head 38 slides downwardly along the latter, the rod 37 is carried downwardly with rod 34 during part of the downward movement 40 of the latter.

Rod 37 extends through a guide opening in bracket 42 and at its lower end is provided with a hub 43, Fig. 9, carrying a pin 45 by means of which it is connected to pairs of links 51, 52. The links 51, 52 are connected by link pins 53 to arms 54 secured to a pair of pivotally mounted end-flap closing plates 40 and 44, respectively, which substantially correspond in width to the space between the side flaps 14, 15 of a carton. The plates 40, 44 are mounted in hinge plates 41, secured on the bracket 42 by hinge pins 41a extending through apertures in the lower ends of the arms 54 so that the flap closing plates may be swung downwardly into contact with the end flaps of a carton positioned on platform 23 for closing these flaps. As shown in Figure 8, the adjacent end portions of plates 40, 44 overlap and the plates are preferably cut away on their upper and lower faces, respectively, so that they may readily assume horizontal positions in closing the end flaps of a carton.

A pair of guide plates 55, 56 for the side flaps of a carton is secured to bracket 42 at each side thereof, the plates of each pair being arranged in spaced relation to provide slots or channels for receiving the side flaps of a carton to hold them in substantially vertical positions during the flap closing operation. The 75

- major portions of the plates 55 are disposed forwardly of flap closing plates 40, 44, the plates 55 extending along only the forward part of the side edges of the flap closing plate 40. The plates 56 extend downwardly from the top part of bracket 42 in spaced relation to the side edges of flap closing plates 40, 44 and partially overlap the plates 55, Fig. 7, from which they are spaced to form the channels for the side flaps. At their lower ends the plates 56 are flared outwardly for guiding the forward parts of the side flaps of a carton into the guide channels as the carton is raised toward the flap-closing plates by the elevating platform 23.
- The reciprocations of rod 34 for raising and lowering platform 23 and of rod 37 for operating the flap closing plates 40, 44 are controlled by a cam 50 or cam shaft 27 acting through a linkage 49 to operate a rock shaft 48, as shown in Fig. 1. A pitman rod 46 adjustably secured adjacent one end to a crank 47 fixed to rock shaft 48 has a bifurcated head 46a connected to rod 34 for reciprocating the latter and, through cross-head 38, the rod 37 also.
- A conveyor chain 75 guided around a sprocket 16 to travel forwardly in spaced relation to the rear side face of a carton is provided at intervals with members 77 extending outwardly therefrom and adapted to engage the rearward end of a carton to carry it forwardly from the end-flap closing apparatus 39 when platform 23 is in its raised position. The spacing of members 77 along chain 75 and the rate of operation of the latter are such that a member 77 does not engage a carton 11 immediately after it has been laterally transferred to platform 23 from belt 10 by the offset-feed device but engages the carton to advance it after the end-flap closing operation has been nearly or fully completed. The operations of conveyor chain 75 and flap closing device 39 are properly coordinated by suitable mechanism operating cam shaft 27 and the conveyor 75. By this means the carton is not advanced from the closing station until the end flaps are at least substantially closed, thus retaining the flakes within the package.
- A plate 80 of a width to fit closely between the side flaps 14, 15 is supported from bracket 42 and is vertically positioned to engage the closed end flaps 12, 13 as the carton is moved forwardly for maintaining them closed until one of the side flaps has been sealed thereover to hold them in closed position. The carton is moved forwardly with its bottom guided on a track 81 with which platform 23 aligns when in its raised position. In the arrangement shown track 81 is disposed above the plane of conveyor belt 10 with which platform 23 aligns when in its lowered position. Guide bars 18, 19, which may be integral angular extensions of the bars 18, 19, are adapted to engage the front side of the carton and together with the back guide 24 engaging the rear side of a carton guide it in its forward movement by chain 75.
- Bracket 42 also supports a pair of plates 83, one at each side of plate 80, provided with suitable camming portions 84 positioned for turning the side flaps 14, 15 downwardly and outwardly to a substantially horizontal position, as illustrated in Figure 4. Air under pressure is directed against the top of the cartons and side flaps 14, 15 through an apertured pipe 85, supported from bracket 42, for removing any soap flakes from the side flaps and top of the carton to prevent flakes getting mixed with adhesive that is

applied to the longitudinal edges of the side flaps as they pass under adhesive applying rolls 86.

Beyond the rolls 86 are plates 87, 88 having camming faces adapted to turn the side flaps 14, 15, respectively, upwardly and slightly inwardly, as illustrated by the position of flap 15 in Figure 5, into position to be engaged by related series of inclined flap closing and sealing rollers 89, 90. The respective rollers of each series have their axes inclined at various angles approaching the horizontal across the path of movement of the top of the carton for turning the side flaps 14, 15 downwardly and pressing them against the end flaps to seal the carton.

The operation is as follows:

Conveyor belt 10 carries the cartons, loosely filled to a level near the top edges of the flaps, forwardly to position them in succession in front of the offset-feed device where the foremost carton is brought to rest by bars 18, 19. The carton 20 upon engaging trigger 30 actuates the latter to trip cam 26 for effecting reciprocation of the offset-feed device. Pusher-plate 22 of the offset-feed device then engages the front side of the carton and moving inwardly, at a rate to obviate jarring the carton and spilling the soap flakes therefrom, transfers the foremost carton from belt 10 to elevating platform 23, which is then aligned therewith, Figs. 8 and 9. Plate 25 carried with the pusher-plate closes the exit at the forward end of guides 17 to temporarily prevent forward movement of the following carton with belt 10.

Cam 50 then acts on linkage 49 to turn rock shaft 48 counter-clockwise causing the pitman rod 46 to raise rod 34 for elevating the platform 23 to move the carton towards the flap closing plates 40, 44. As platform 23 is raised the flared portions of plates 56 guide the forward parts of the side flaps 14, 15 into the channels between these plates and plates 55 to hold the side flaps in vertical positions, as illustrated in Figure 7, for maintaining them out of the way of flap closing plates 40, 44. When rod 34 is raised it slides the cross-head 38 secured thereto along rod 37 to engage the latter with the nuts 37a on the rod to raise the latter also. As rod 37 is raised it draws the links 51, 52 toward each other and the latter act through the arms 54 to swing the plates 40, 44 downwardly about hinge pins 41a into engagement with the end flaps 12 and 13, respectively.

The simultaneous pivoting movements of closer plates 40 and 44 in opposite directions as they are brought into contact with the end flaps turn both flaps inwardly and downwardly at the same time and cause the soap flakes located between the upstanding flaps to be pressed downwardly into the body of the carton and compressed by the end flaps 12, 13 as they are closed. The side flaps 14, 15, which are held vertically between plates 55 and 56, guide the soap flakes into the body of the carton and prevent their being forced or spilled over the sides. As shown in Figures 8 and 9, plate 44 is provided with perforations permitting the escape of air that may be expressed as the flakes are compressed in the carton.

As the plates 40, 44 are swung downwardly toward horizontal positions by the rod 37, the rod 34 continues to elevate the platform 23 moving the carton toward the down-swinging closer plates and pressing the end flaps of the carton against these plates so that the material located between the side and end flaps is forced into the body of the carton under pressure exerted from

both above and below by the plates 40, 44 and platform 23, respectively. This application of pressure to the soap flakes does not result in breaking them or removing the crinkle therefrom since the pressure applied to press the material into the body of the carton is considerably less than that which would be required for forcing an excess quantity of soap flakes into a carton by means of a plunger, as mentioned above. 5 Moreover, the cam 50 is preferably designed with a contour or groove providing a harmonic motion so that while the rods 34, 37 may move fairly rapidly in the early part of their upward (and downward) movements, the latter part of their 10 upward movement takes place at a more gradual rate so that as the end flaps approach their fully closed positions the pressure exerted through the action of plates 40, 44 and platform 23 is applied gently and gradually as the compression of 15 the flakes increases.

When the end flaps are closed the operation of conveyor chain 75 brings a member 77 thereon into contact with the rear end of the carton for advancing it from beneath closing device 39. 20 Since the plates 55 and 56 extending along the sides of bracket 42 are supported at their forward and upper edges, respectively, the carton may be moved forwardly without interference as the side flaps 14, 15 are free to move out of the channels 25 between these plates.

Pusher plate 22 of the offset-feed device is maintained positioned against the front side of the carton holding it against the guide bar 24 as flaps 12, 13 are closed. The offset-feed device is 30 then operated by cam 26 to return pusher-plate 22 quickly to its outer position for transferring another carton to platform 23 and plate 25 is moved outwardly therewith from across guides 17 to permit belt 10 to position the following carton in front of the offset-feed device.

As end flap 13 is moved from contact with plate 44 it engages plate 40 which holds both flaps 12 and 13 closed and as the carton is advanced from beneath the closing device 39 the end flaps become engaged with the stationary plate 80 which fits closely between the side flaps and bears against the end flaps to hold them in their closed positions.

Cam 50 acts through linkage 49, rock shaft 48, and pitman rod 46 to depress rod 34 lowering the platform 23 from alignment with track 81 into alignment with conveyor belt 10 for receiving the following carton therefrom. As rod 34 is depressed the end of cross-head 38 that embraces rod 37 slides therealong until the end of member 38a on the cross-head that overlies the rod 37 engages the end of the latter. The rod 37 is then lowered in unison with the rod 34 so that the links 51, 52 are spread and the plates 40, 44 swung upwardly about their hinge pins in preparation for closing the end flaps of the next carton.

As conveyor 75 advances the carton its side flaps 14, 15 engage the camming faces 84 of plates 83 so that they are turned outwardly and downwardly to horizontal portions, Figure 4, to pass beneath the rolls 86 to receive adhesive adjacent their side edges. Subsequently, flap 14 on engaging plate 87 is turned upwardly and slightly inwardly into position to pass beneath the inclined rollers 89 which turn the flap down and press it against the end flaps as the carton advances, as illustrated in Fig. 5. As shown in Fig. 1, stationary plate 80 which fits over the end flaps to hold them closed extends forwardly far enough beneath rollers 89 to hold these flaps closed until

they are sealed by flap 14. The plate 88 and rolls 90 turn flap 15 upwardly and then over the flap 14, as shown in Figure 6, to complete the sealing of the carton.

Although a carton receives a quantity, for example, of loose soap flakes or other bulking material filling it to a level between the upstanding flaps this quantity need not exceed the usual weight of material which the carton is intended to contain inasmuch as the soap flakes are put in the carton in their natural crinkly and unbroken form and thus bulk to a volume sufficient to fill the carton as described. Due to the fact that the flakes are not crushed before closing the flaps by a plunger operating under heavy pressure but are gently pressed down, without crushing, into the carton by the end flaps as they later are folded inwardly, they remain substantially in their natural unbroken state and due to their relatively 10 resilient nature tend to resume their original condition when the flaps are opened.

The compression of the flakes by the end flaps causes the carton to bulge slightly at the sides and, because these flaps are held fully closed by plate 80 until a side flap has been sealed thereover, the carton is fully closed and sealed in this condition. As a result, the usual settling of the flakes due to natural readjustments or to jarring of the cartons in transit does not manifest itself as a shrinkage in volume of the contents to a 20 level objectionably below the top of the carton but results in relieving the flakes to a degree from the compressing action of the flaps. In fact it has been found that cartons filled and sealed by apparatus constructed in accordance with the 25 invention often reach the consumer with the flakes still under sufficient compression so that when the flaps are opened the contents bulge slightly from the top of the carton with the result that the consumer receives the more favorable 30 impression that the carton has been overfilled. Moreover, the contents of the carton are less subject to breakage due to abrasion of one particle with another and to shaking on handling because when the carton does not have an empty space at 35 the top, but is full and its contents under pressure, the contents of the carton are less likely to move about.

Although a specific embodiment of the invention has been described in detail, there are many 50 changes and variations which may be made without departing from the invention and, therefore, it is desired and intended to include all such changes and variations within the scope of the 55 following claims.

I claim:

1. Apparatus for closing flaps extending upwardly from opposite edges at the top of a carton comprising; a movable carton support; a pair of flap closing members pivotally mounted in opposed relation and each adapted to engage one of a pair of opposed flaps of a carton on said support; means for moving said plates about their pivots into engagement with said opposed flaps for folding them inwardly to closed positions; and means for moving said support toward said members to press said pair of flaps against said members.

2. Apparatus for closing flaps at opposite edges of the top of a carton filled with loose bulky material to a level between the upwardly extending end and side flaps thereof comprising; a pair of flap closing members movably mounted in opposed relation and each engageable with one of a pair of opposed flaps of a carton to fold it inwardly 70

5 to closed position; a carton support movable toward said flap closing members; and means for moving said members into engagement with said flaps and for simultaneously moving said support towards said members to compress the material located between the upstanding flaps into the body of the carton and to close the said opposed flaps.

10 3. Apparatus for closing flaps at opposite end edges of the top of a carton comprising; a movable carton support; a pair of flap closing members movably mounted in opposed relation and positioned to be moved between the upstanding side flaps of a carton on said support into engagement with the end flaps of the carton to fold them inwardly to closed positions; means mounted adjacent said members for engaging and holding the side flaps of a carton in substantially vertical positions out of the path of movement of 15 said end-flap closing members; and means for moving said support toward said members to engage the side flaps of a carton thereon with said holding means.

20 4. Apparatus for closing flaps at opposite end edges at the top of a carton filled with loose bulky material to a level between the upstanding end and side flaps thereof comprising; a movable carton support; a pair of movable end flap closing members mounted in opposed relation to be 25 moved between the upstanding side flaps of a carton on said support to fold them inwardly to closed positions; means for simultaneously moving said members into engagement with said end flaps to compress the material located between 30 the upstanding flaps into the body of the carton and to close the end flaps in unison; means mounted adjacent said members and engageable by said side flaps for holding them in substantially vertical positions to prevent spilling of material from 35 the sides of a carton during closing of the end flaps; and means for moving said support towards said members to engage the side flaps with said holding means and to subsequently press the end flaps against said members.

40 45 5. In apparatus for closing flaps extending upwardly at opposite edges of the top of a carton; a closing station; a movable carton support at said station; a pair of flap closing members mounted in opposed relation at said station for 50 movement to engage and close opposed end flaps of a carton; conveying means for advancing car-

tons to said support; means disposed out of the plane of said conveying means for carrying cartons away from said station; means for moving said carton support to position the carton in the plane of said carrying means; and means for operating said closing members for engaging and closing end flaps of a carton on said support. 5

6. In apparatus for closing flaps extending upwardly at opposite edges of the top of a carton; a closing station; a movable carton support at 10 said station; a pair of flap closing members mounted in opposed relation at said station for movement to engage and close opposed end flaps of a carton; conveying means for advancing cartons to said support; means disposed out of the 15 plane of said conveying means for carrying cartons away from said station; and means for moving said carton support to press end flaps of a carton thereon against said closing members and to position said carton in the plane of said 20 carrying means.

7. Apparatus for closing flaps extending upwardly at the top of a carton comprising; a pair of flap closing members mounted in opposed relation and each adapted to engage one of a pair 25 of opposed flaps; individual means supporting said members between their ends for pivotal movement; a reciprocable member; and individual pairs of links associated with said closing members and said reciprocable member, the links 30 of each pair having their adjacent ends interconnected and their opposite ends connected respectively to one of said members and to said reciprocable member for transmitting the movement of the latter to said flap closing members 35 for pivoting them in opposite directions.

8. Apparatus for closing flaps extending upwardly at the top of a carton comprising; a pair of flap closing members mounted in opposed relation and each adapted to engage one of a pair 40 of opposed flaps; individual means supporting said members between their ends for pivotal movement; a member reciprocable toward and away from the top of a carton in a path between the pivots of said closing members; and individual linkages connecting said closing members to said reciprocable member for pivoting them in opposite directions into engagement with the 45 carton flaps upon movement of said reciprocable member in a direction away from the carton. 50

BERNARD L. MAXWELL.
